UNIVERSAL DENTAL CAPSULE FILLER FOR
USE BY THE DENTAL PROFESSION

John Marcus Shoemaker, Sr., Middletown, Ind.

Application May 20, 1948, Serial No. 28,137

5 Claims. (Cl. 226—40)

1

My invention relates to an improved device for filling capsules with alloy and mercury used by the dental profession. The device consists of a block for holding or supporting a capsule, a slide block into which the capsule supporting block is inserted, and a housing into which the slide block is passed and through which the materials are delivered to the capsule.

The object of this invention is to provide a device for securely holding a capsule so that it may be filled with the alloy and mercury in an expeditious and sanitary manner. The device simplifies processing and avoids touching by hand.

A further object is to provide a method of filling various kinds of capsules.

A further object is to permit all types of capsules to be removed with a minimum of difficulty.

Fig. 1 is a plan view of the assembled device.

Fig. 2 is a front elevation of the assembled device.

Fig. 3 is a sectional view of the assembled device along line 3—3 of Figure 1 showing block, slide, and capsule in place.

Fig. 4 is a plan view of the slide.

Fig. 5 is a plan view of a typical block.

Fig. 6 is a front view of a typical block.

Fig. 7 is a side view of a typical block.

Fig. 8 is a side view of the slide with block and capsule inserted.

The device consists of a rectangular housing 11, surmounted by a circular offset 12 which extends a little above the upper surface. Offset 12 is surmounted by offset 13, also circular, and somewhat smaller in size than offset 12. Offset 13 extends a little above offset 12. A smoothly tapered hole 14 extends through offsets 12 and 13 and the upper wall of the housing 11, terminating in a channel 16 therein. The hole 14 is larger in diameter on the outer surface of the assembly than on the inner surface, being of conical formation and the outer end is faired smoothly into the upper surface of upper offset 13. The sides of housing 11 curve outward about halfway toward the bottom and become vertical again to broaden the base. A rectangular channel 16 passes completely through housing 11 from the forward to the rear sides. The channel is open to the outside of the housing by virtue of tapered hole 14 leading through the upper surface of the housing.

Slide block 15 is roughly rectangular in shape, and is a solid block except for apertures hereinafter described. Slide block 15 fits within

2

channel 16 of housing 11. To the front end of the slide block is attached plate 17 which is also rectangular and slightly larger in area than the channel 16. Attached to plate 17 is handle 24 which is roughly cylindrical in shape and extends a short distance beyond the plate. In the center of the slide block 15 is a hole 19 or pocket which is circular in cross section, sufficiently less in diameter than the width of the slide block to permit a thin wall at the edge of the slide block adjacent to the major diameter of the hole. At this point, the top of the thin-wall portion of the slide block is cut out in a semi-circle, decreasing the depth of the hole or pocket. Elsewhere, the hole extends about seven-eighths of the depth of the slide block. Forward and aft of the hole 19 are two apertures or pockets 23, semi-circular in transverse cross-section and rectangular in plan view, extending with the short dimension in a forward and aft direction. These apertures have a depth of about one-fourth of the depth of the slide block, a length slightly less than the width of the slide block, and a width about one-half the length.

25 A capsule supporting block 18 fits into hole or pocket 19, and is circular in cross-section to fit the hole 19. In the center of the capsule supporting block 18 is hole or recess 21, circular in types of capsule supporting blocks. The hole or recess 21 has a depth about seven-eighths the depth of capsule supporting block 18. Two diametrically opposite segments of the upper surface of the capsule supporting block 18 are cut away for a depth of about one-fourth that of the block, leaving two exposed fingers with a width approximately equaling the diameter of the hole 21.

30 The operation of the device is as follows: Capsule 20 is placed into hole or recess 21 of the capsule supporting block 18, which is designed to hold the capsule snugly in place, and leave a sufficient portion of the capsule protruding above the surface thereto so that the capsule may be easily removed by grasping with thumb and forefinger. This is possible because of the cutaway portion of the capsule supporting block as previously described. The capsule supporting block 18 is then placed in hole or pocket 19 of slide block 15 by grasping it by the fingers 22, or by 35 the sides of the block exposed by the semi-circular cutaway of sides of slide block 15; thus the position of the capsule is undisturbed. The capsule supporting block may be any of several types in accordance with the size of capsule to be filled, but all capsule supporting blocks have the same

exterior dimensions to permit an interchangeable fit into hole or pocket 19. Substitution of capsule supporting blocks is simplified by the absence of screws or other fastening devices, since gravity is sufficient to keep them in place. Slide block 15 is then inserted into channel 16 of housing 11, and is securely held in place by the four walls of the channel. These walls serve to keep the slide block, and accordingly the capsule supporting block and capsule in a definite horizontal and vertical relation to housing 11, while plate 17 contacts the front walls of housing 11 and maintains a fixed relation to housing 11 in a fore and aft direction. With the slide block in this position, capsule 20 is directly under tapered or conical filler hole 14, and the alloy and mercury are delivered through hole 14 into capsule 19. When the filling operation is complete, slide block 15 is pulled back out of channel 16 by means of handle 24, and the capsule is extracted from hole or recess 21 of capsule supporting block 18. The device is then in readiness for additional operations.

I claim:

1. A dental capsule filler comprising a housing having a top wall with an opening therein surrounded by a conical wall, a reciprocating block interfittingly slidable in said housing, said block having an upwardly opening central pocket therein, a capsule supporting block removably mounted in said pocket and having a center recess for the support of a capsule and means at the outer end of the slide block adapted for abuttingly engaging the adjacent end of the housing

10

4
for aligning the capsule with the opening in the top wall of the housing.

2. A dental capsule filler as in claim 1, wherein said housing is open at opposite ends and the means on the slide block abuttingly engaging the housing includes an outwardly directed flange on the outer end of the slide block.

3. A dental capsule filler as in claim 1, wherein the side walls of the pocket at diametrically opposite sides of the slide block are cut away adjacent the upper end of the block to facilitate removal of the capsule supporting block when the slide block is removed from the housing.

4. A dental capsule filler as in claim 3, wherein diametrically opposite upstanding gripping fingers are carried by the upper end of the capsule supporting block.

5. A dental capsule filler as in claim 4, wherein a pocket for auxiliary capsules is formed in the upper face of the slide block adjacent each end thereof and outwardly of said central pocket.

JOHN MARCUS SHOEMAKER, SR.
